STOP MOTION FOR KNITTING MACHINES

Jacob Wachsman and David Wachsman, Brooklyn, N. Y.; said Jacob Wachsman assignor to David Wachsman

Application February 17, 1953, Serial No. 337,346

1 Claim. (Cl. 66—163)

1

This invention relates to improvements in stop motions for knitting machines of the type disclosed in the U. S. Patent No. 2,368,184, January 30, 1945. In improving the stop motion disclosed in the patent the object of the invention is to provide a more efficient compact mechanism embodying certain details of improved construction and design whereby the operation of a stop motion of this type becomes more certain, produces less wear and eliminates certain defects in the prior disclosure. The advantages and features of the invention will be readily understood from the following specification read together with the accompanying drawing in which

Fig. 1 is a front view of the stop motion with parts removed and parts broken away.

Fig. 2 is a similar view with the parts in position when the mechanism has been operated.

Fig. 3 is a sectional view on the line 3—3 of Fig. 2 with parts omitted.

Fig. 4 is a sectional view on the line 4—4 of Fig. 1 with parts omitted.

Fig. 5 is a diagram illustrating the operation of the device.

Referring first to Figure 5 the numeral 10 indicates conventionally the stop handle of a knitting machine drive. When the handle is swung on its pivot, the driving mechanism, not shown, is operated to stop the machine, the operation being similar to that of a belt shifting mechanism. The operation of the stop handle is controlled by a travelling thread. The control mechanism is in the form of a switch in which a movable member 11 is supported on the thread 12 which travels over guides 13. When the thread breaks or runs out the member 11 drops and contacts a fixed member 14 to close a normally open electric circuit. The member 14 is grounded. The movable member 11 which sometimes is called an end detector or knot detector is connected to a battery 15, an electromagnet 16 and a contact spring 17. The latter is normally grounded by contact with a movable plunger 18 which actuates the handle 10. The magnet has a pivoted armature 19 which is attracted when the magnet is energized by the closure of the electric circuit. This occurs when the thread 12 fails to keep the switch 11—14 open. Normally the plunger is prevented from operating the stop handle by means of a stop lever, not shown in Fig. 5 but which will be explained later. The stop lever in turn is held in position to prevent release of the plunger by the unattracted armature. When the circuit is closed the armature is attracted, the stop lever is operated so that it no

2

longer prevents the operation of the plunger. The latter is then operated and in turn actuates the stop handle to stop the machine.

Referring now to Figs. 1—4 the improved stop mechanism is supported within a box 26 which is secured to the knitting machine with the plunger 18 in position to engage the machine stop handle as will be understood. The box has a cover 27. The magnet 16 is suitably supported in the box as shown. One end of the magnet wiring is connected to a fixed terminal 28 for attaching the wire from the battery 15. The other end of the magnet wiring is connected to the spring 17 for grounding the circuit on the machine.

The plunger 18 is slidably mounted in the sides of the box and a block 29 is secured to the plunger as by one or more screws 30. A guiding shaft 31 is secured in the box by a pin 32 and passes through the block 29. Thus the block and the plunger are securely guided in the box and the block cannot turn on the plunger and become jammed in its movements. This is a decided advantage and a feature of the improved mechanism.

The block is formed with a contact nose 33 which normally engages the spring 17. On the opposite side the block 29 has a finger 34 with a hook 35, Fig. 3, adapted to engage a stop lever 36. The latter is pivoted at 37 in a cut out portion 38 of the box. The free end of the stop lever rests upon a stop 39 which is part of the armature 19. The latter is pivoted upon a shaft 40 and is held away from the magnet 16 by a spring 41. The stop lever 36 has a recess 42 and the hook 35 on the block 29 is shaped to engage the recess.

In the normal position of the parts as in Fig. 1 the plunger 18 with the block 29 is pushed by the operator into the position shown and as the block finger 34 moves in over the stop lever 36, the hook 35 finally drops into the recess 42 so that the stop lever is lifted and lies in a position parallel to the plunger 18. This is seen in Fig. 4 where only the end of the stop lever appears as a consequence of this movement. A spring 44 acting against the lower edge of the stop lever insures constant operative contact between the lever and the block finger 34, as seen in Fig. 3. As the hooked block finger moves into its normal position, the spring 44 exerts a lifting pressure upon the lever and thus insures that the recess in the lever will be positioned to receive the hook 35 and the lever reaches its final normal upper position.

A plunger spring 45 is placed on the plunger 18 and the spring constantly tends to push the

stop lever aside or downward by a movement about its pivot 37. The recess 42 is merely a slight inclined edge and unless the stop lever is held by some other means, the finger hook 35 will jump out of the recess and release the stop lever because of the constant pressure by the spring 45 against the block 29. If the hook should jump the recess there is nothing to prevent the plunger from being operated by its spring 45. However, so long as the free end of the stop lever 38 rests upon the armature stop 39, the stop lever cannot move about its pivot 37.

The operation is as follows: Figs. 1 and 4 show the parts in their normal positions. The stop lever is under constant pressure by the spring 10 pressed finger 34, the hook 35 seeking to jump out of or away from the recess. The armature stop 39, Figs. 1 and 3, prevents such movements.

When the circuit is closed the armature stop is withdrawn from the stop lever as the armature is attracted by the magnet 16. The stop lever therefore no longer resists the pressure of the spring 45 which thereupon moves the plunger into position to stop the machine. Resetting the plunger puts the parts back into normal positions, the stop lever being lifted by the sliding movement of the block finger until the hook again engages the recess and the armature stop is moved in under the stop lever by the armature spring 41. When the circuit is closed the stop lever is released from the armature stop and the plunger is violently moved outward.

The armature stop 39 may also be moved out from under the stop lever by a pin 50 adapted to be depressed by a pivoted lever 52 which is connected as at 53 with the take-up mechanism of the knitting machine. This mechanism is shown diagrammatically in Fig. 5 by the usual take-up guiding rolls 54 which guide the fabric 55 as it comes from the knitting machine, not shown. When for any reason the knitting mechanism of the machine fails in its normal operations, the take-up device will fall down so that the lever 52 will move down also and depress the pin 50. Thus the armature stop will be moved away from under the stop lever and the stop motion will be operated the same as when the circuit is closed.

Depending upon the make of the knitting machine, it may be desirable to position the plunger 18 closer to one side of the box than as shown. 50

This may be done by merely exchanging the positions of the plunger 18 with that of the guide shaft 31. The latter and the plunger are therefore interchangeably mounted in the box. This is an important advantage in the actual fitting of the stop mechanism to a particular make of knitting machine.

It is also important that the device as a whole be as simple and compact as possible and that all movable elements are under control. The certain straight movement of the plunger 18 and the block, guided as it is by the shaft 31, insures that no part of the mechanism becomes jammed or out of control.

We claim:

In a stop motion for knitting machines which include a stop handle and an electric circuit with a normally open switch controlled by a travelling thread, said stop motion comprising a box, a plunger slidably supported therein, a spring on said plunger for moving the same to actuate the said handle to stop the knitting machine, means for guiding said plunger in its movements within the box comprising a fixed guide shaft therein in parallel relation to said plunger, a block member secured to the plunger and sliding upon the said guide shaft, a pivoted stop lever in said box, means on said stop lever engaging said block member to hold said plunger immovable against the action of the said plunger spring, a projecting armature stop engaging said stop lever to hold the same in operative engagement with said plunger, a stop lever spring in said box engaging said stop lever to hold the same in operative contact with said block member during the movements of said plunger, an electromagnet in said circuit for operating the said armature stop to release said stop lever when said circuit is no longer under control of the travelling thread, said guide shaft and said plunger being interchangeably supported in said box and in relation to the said block member.
